DESIGN FOR A BADGE OR ARTICLE OF SIMILAR NATURE

Charles S. Amspacker, Columbus, Ohio

Application February 22, 1944, Serial No. 112,671

Term of patent 7 years

(Cl. D29—2)

To all whom it may concern:

Be it known that I, Charles S. Amspacker, a citizen of the United States of America and a resident of Columbus, in the county of Franklin and State of Ohio, have invented a new, original, and ornamental Design for a Badge or Article of Similar Nature, of which the following is the specification, reference being had to the accompanying drawing, forming a part thereof.

Figure 1 is a perspective view of the badge or article of similar nature showing my new design.

I claim:

The ornamental design for a badge or article of similar nature, substantially as shown.

CHARLES S. AMSPACKER.
